UNITED STATES PATENT OFFICE.

ALBERT J. FORD, OF NEW YORK, N. Y., ASSIGNOR TO THE FUCHS & LANG MANUFACTURING COMPANY, OF SAME PLACE.

BRONZING-MACHINE.

SPECIFICATION forming part of Letters Patent No. 653,952, dated July 17, 1900.

Application filed November 7, 1899. Serial No. 736,093. (No model.)

To all whom it may concern:

Be it known that I, ALBERT J. FORD, a citizen of the United States, residing in the city of New York, borough of Brooklyn, and State 5 of New York, have invented certain new and useful Improvements in Bronzing-Machines, of which the following is a specification.

This invention relates to certain improvements in bronzing-machines for bronzing lithographs and other sheet articles by which the bronze-powder is uniformly distributed over the parts to be bronzed, thoroughly rubbed in, and the surplus removed from the unbronzed or bronzed parts.

15 The invention consists of a bronzing-machine which comprises a bronze-hopper, a distributing-roller below the same, means for feeding the sheet or plate forward, a rubbing-brush adjacent to said distributing-roller, a 20 frame for supporting said brush, means for imparting a gyratory motion to said brush, said means comprising vertical shafts journaled in said frame and provided with eccentric portions journaled in bearings of the 25 brush-back, a transverse shaft journaled in bearings of said frame, bevel-gearing connecting the transverse and vertical shafts, means for rotating said transverse shaft, and dusting means beyond the rubbing-brush.

30 In the accompanying drawings, Figure 1 represents a side elevation of my improved bronzing-machine. Fig. 2 is a vertical longitudinal section of the same drawn on a larger scale. Fig. 3 is a plan view of the machine; and Fig. 4 is a detail vertical transverse section, drawn on a larger scale, on line 35 4 4, Fig. 2, parts being in elevation and showing the rubbing-brush.

Similar letters of reference indicate corresponding parts.

Referring to the drawings, A represents the supporting-frame of my improved bronzing-machine for lithographs, &c. At the ingoing end of the machine is arranged an inclined feed-table B, formed of a number of parallel longitudinal slats b, on which the lithographic sheets, plates, signs, or other sheet articles to be bronzed are placed. 45 Parallel with the inclined feed-table B is arranged a reciprocating rod C, which is guided in a suitable keeper d at the under side of the ta-

ble, said rod being connected with the shank e of a pusher D, which is reciprocated upon the feed-table and which is adjusted by its shank on the reciprocating rod C, so that one 55 sheet after the other may be fed to the operating parts of the bronzing-machine. The reciprocating pusher-operating rod C is connected by a short pivot-link e' with a lever-arm C', which is fulcrumed to a transverse 60 shaft C^x, extending between the sides of the frame A of the machine, said lever-arm being connected with a strong helical spring C², so as to have a tendency to move in an inward direction. The lever-arm C' is connected 65 above its fulcrum with a slotted connecting-rod C³, which is guided by its slotted portion upon the driving-shaft S and provided with an antifriction-roller r, that moves along a cam r' on the driving-shaft S. The cam r' is 70 so shaped that an oscillating motion is imparted to the lever-arm C', so as to reciprocate the rod C of the pusher D to the required extent.

At the middle portion of the supporting-frame of the machine is arranged a bronze-hopper E, of the usual construction, which is supplied with bronze-powder, said powder being transmitted by a distributing-roller E', covered with plush or other suitable soft material, to the paper sheets or signs or tin or other metal plates that are moved over the feed-table by the pusher D. Intermittent or step-by-step rotary motion is imparted to the distributing-roller E' by a cam and suitable 80 transmitting mechanism from the driving-shaft S, as shown in dotted lines in Fig. 2, preferably by a ratchet-and-pawl device M, which is operated by a pivoted lever M' and actuating-cam M². 90

Adjacent to the bronze-hopper E and its distributing-roller E' is arranged a rubbing-brush F, which consists of two parallel brushes f f, which are attached to a suitable back f'. A frame F' is supported on brackets f² of the side standards of the machine and is adjusted by means of set-screws f³ relatively to the surface to be bronzed. A gyrating motion is imparted to the rubbing-brushes f by a transverse shaft f⁴, that is driven by a belt-and-pulley transmission N N' N² and a gear-wheel-and-pinion transmission P P' from the 95 100

driving-shaft S. The shaft f^4 transmits rotary motion by bevel-gears $f^5 f^6$ to short vertical shafts f^7 , which turn in bearings f^8 of the frame F'. The shafts f^7 are connected by eccentric shafts f^9 with bearings f^{10} on the brush-back f' , so that a gyrating motion is imparted to the same and the brushes, and thereby a rubbing action exerted on the bronzed surfaces. By the rubbing action of the brushes the bronze-powder is uniformly rubbed over the sized portions of the surfaces of the sheets and incorporated with the same. The sheet or plate is then conducted from the rubbing-brush forwardly between a series of feed-rolls G and over stationary tables g, between said feed-rolls, and is acted upon by a number of so-called "dusting-rolls" H, which are formed of suitable material and which remove the bronze-powder from the unsized portions of the surfaces. The feed-rolls G are all turned in the same direction by means of a series of intermeshing pinion and gear wheels O O' O², while the dusting-rolls H receive rotary motion in opposite direction thereto by means of a belt-and-pulley transmission T T', an auxiliary shaft S', to which rotary motion is transmitted from the intermediate shaft S², and gear-wheels V and pinion V', as shown in Fig. 1. The transmitting gear-wheels O² turn loosely on the shafts of the dusting-rolls H, so as not to affect the latter. The shafts of the dusting-rolls H are supported in journal-bearings H', which are capable of adjustment, so that the dusting-rolls can be accurately adjusted to the sheets or plates to be bronzed. The first two dusting-rolls receive direct rotary motion by a belt-and-pulley transmission from the auxiliary shaft S' at one side of the machine, as shown in Fig. 1, while the remaining dusting-rolls are rotated by a belt-and-pulley transmission at the other side of the machine, but from the same auxiliary shaft. Below the last dusting-roll is arranged a second dusting-roll H', which removes any powder that may have passed to the under side of the sheet. The dusting-rolls are inclosed by a suitable sheet-metal casing I, which is hinged at its outer end at i to the end

of the supporting-frame A and which is lifted into upright position by means of a chain W whenever it is desired to obtain access to the dusting-rolls for adjusting, cleaning, or repairing the same. To the inside of the casing I are applied partitions I', that extend downwardly over the dusting-rolls, so as to prevent the bronze-powder from being passed over to the adjacent preceding dusting-roll or feed-rollers. The casing is provided at its outgoing end with an inclined wall I², that extends toward the last set of feed-rolls, as shown in Fig. 2.

The bronze-hopper, with its distributing-brush, as well as the feed-rollers and dusting-rolls, are well known and I do not claim the same; but I do claim the rubbing-brush adjacent to the distributing-brush and the mechanism for imparting gyrating motion thereto and by which the bronze-powder is rubbed into the sized portion of the surfaces of the sheets or plates to be printed.

Having thus described my invention, what I claim as new, and desire to secure by Letters Patent, is—

In a bronzing-machine, the combination, with the bronze-hopper and distributing-roller below the same, of means for feeding the sheet or plate forward, a rubbing-brush adjacent to said distributing-roller, a frame for supporting said brush, means for imparting a gyratory motion to said brush, said means comprising vertical shafts journaled in said frame, and provided with eccentric portions journaled in bearings of the brush-back, a transverse shaft journaled in bearings of said frame, bevel-gearing connecting the transverse and vertical shafts, means for rotating said transverse shaft, and dusting means beyond the rubbing-brush, substantially as set forth.

In testimony that I claim the foregoing as my invention I have signed my name in presence of two subscribing witnesses.

ALBERT J. FORD.
